(57) **CLAIM**

The ornamental design for a flexible container support frame, shown and described.

DESCRIPTION

FIG. 1 is an isometric view from above of the flexible container support frame of the design;

FIG. 2 is an isometric view from below of the support frame of FIG. 1;

FIG. 3 is a side elevation of the support frame. The side elevations from the remaining three sides are identical;

FIG. 4 is a top plan view of the support frame of FIG. 3; and,

FIG. 5 is a bottom plan view of the FIG. 3 support frame.
